UNITED STATES PATENT OFFICE.

WILLIAM E. EASTMAN, OF BOSTON, MASSACHUSETTS.

AIR-MOTOR.

SPECIFICATION forming part of Letters Patent No. 278,228, dated May 22, 1883.

Application filed December 7, 1882. (Model.)

To all whom it may concern:

Be it known that I, WILLIAM E. EASTMAN, a citizen of the United States, residing at Boston, in the county of Suffolk and State of Massachusetts, have invented certain new and useful Improvements in Air-Motors, of which the following is a specification, reference being had therein to the accompanying drawings, in which—

10 Figure 1 is a side elevation of a motor-engine constructed in accordance with my invention. Fig. 2 is a section of the same with the diaphragm distended. Fig. 3 is a similar view, with the diaphragm collapsed or in a horizontal position. Fig. 4 is a view of a modification showing valve devices. Fig. 5 is a view of the cam and valve-rod detached.

Similar letters of reference in these several figures denote the same parts.

20 The object of my invention is to provide an economical motor-engine for using compressed air, steam, or other elastic fluid, and, further, to do away with much friction now incident to machines or engines of this character.

25 While I do not intend to limit myself to the use of compressed air, I describe the use of my motor therewith for convenience.

By reference to the drawings, it will be seen that the disk or plate B, which is rigidly secured to the piston-rod b, is actuated by an elastic expandible diaphragm, A, which is forced upward by the pressure of air entering the chamber from below by the pipe G. The hole or opening a at or near the center of the diaphragm is considerably larger than the diameter of that portion of the piston-rod b extending below the plate B. This plate B is analogous to and for convenience may be considered the piston-head of the engine. Upon

40 admission of air under pressure to the chamber it would naturally be supposed that it would escape by the opening a, and after having forced the piston head or plate B a short distance away from the diaphragm it would then continue to flow uninterruptedly without imparting further motion to any part of the machine. This, however, is not the case. As soon as the plate or piston-head is forced down upon the diaphragm the expansive force of the 45 air within the chamber is exerted not only upon the plate through the opening a, (and of course upon the lower end of the piston-rod,) 50

but upon the whole surface of the diaphragm as well, which readily yields and transmits a pressure proportional to the area in contact with the plate or piston-head. The escape, then, of all except a thin stratum of air being prevented, the pressure within the chamber causes the elastic expandible diaphragm B to bulge vertically and expand, carrying the piston upward with it and rotating the crank-shaft E and balance-wheel F. At a certain point, however, (which should be when the crank-wrist is a little above the center of the shaft,) the diaphragm becomes so distended and tense that it cannot any longer follow the plate up and give power to it and the momentum of the balance-wheel F carries the plate or piston-head away from it, uncovering the opening a. At this point the pent-up air with- 70 in the chamber quickly and easily escapes through the now distended opening a, which is normally enough larger than the piston-rod to allow all the air entering the chamber to escape when the plate is not in contact with 75 the diaphragm, and which is considerably enlarged when the diaphragm is distended. It will be readily understood that notwithstanding the constant flow of air to the chamber the diaphragm is not thereby prevented from 80 resuming a horizontal or very nearly horizontal position, and, also, that no air escapes when the plate or piston-head is in contact with the plate, and is held there by the slight resistance due to the working parts of the ma- 85 chine. Now, by momentum of the balance-wheel, the crank completes its revolution, bringing the plate again down to the diaphragm, when the same force acts, another stroke is made, and the engine keeps up a steady mo- 90 tion. Details of construction may be varied to suit requirements in different cases; but the principle involved in the action is the same.

As here shown the machine consists of a bed-piece, C, (circular in horizontal section,) 95 with legs. This bed-piece is slightly sunken or chambered upon its upper surface, with the exception of a narrow rim upon which the peripheral portion of the diaphragm rests. This chamber or cavity in the bed-piece may be considered the equivalent of the cylinder in a steam-engine. The bed-piece is screw-threaded around its circumference at the top, and the top piece, D, likewise circular in horizontal

section at its base, is also threaded upon its inside circumference to screw down upon the bed-piece and hold firmly the diaphragm.

To prevent wrinkling and displacing of the diaphragm by the action of the top piece when screwed down, I introduce a metal ring, K, smooth upon its upper surface, to allow the top piece to slide over it, and press it down upon the top of the diaphragm.

10 As will be seen, the top piece, D, is provided with upwardly-projecting arms which carry at their tops journal-boxes for the crank-shaft E, which carries at one of its ends the balance-wheel F, and to which is connected the piston-rod, as hereinbefore set forth. The action of this motor is very rapid, and although it can be made of large size to give considerable power, it is best adapted to running light machinery, hand-tools, and the like—such, for instance, as dental pluggers and excavators, small grinding-tools, perforating-pens, and, generally, tools and instruments of that class where rapid motion and little power are required.

25 In Figs. 4 and 5 the motor is shown with a valve attachment, which, though not essential to the working of the machine, I apply to economize the compressed air. In this case the air, instead of entering at the central portion 30 of the chamber, enters by the induction-port g, very near the side of the chamber. A valve-rod, I, armed at its upper end with a friction-roller, L, and at its lower end with a ball or hemisphere of suitable material, preferably soft rubber, receives proper motion from the cam H, mounted upon the crank-shaft E. This cam is so set that just as the exhaust occurs it forces down that portion of the diaphragm immediately above the induction-port. This 40 portion of the diaphragm, acting as a stopper, prevents the entrance of more air to the chamber until, at the proper time, (which is just as, in its descent, the plate B reaches the diaphragm,) the valve-rod, released by the cam, in turn relieves the diaphragm. The valve-rod does not require any spring to keep it in contact with the cam, as it rides continuously upon the diaphragm. The opening through the arm through which it passes is so 50 constructed as to keep the friction-roller always parallel to the cam, and to give to the valve-rod a true reciprocating motion in a right line.

As shown in the accompanying drawings, the piston-rod is coupled direct to the crank, 55 which subjects the plate B to a slight tilting, due to the horizontal throw of the crank. This in small machines, where such throw is slight, is not objectionable, a short stroke and quick motion being desired; but in larger machines 60 the piston-rod may be provided with a cross-head running in ways, and the connection to the crank be made in the manner usual in steam-engines by a connecting-rod. This modi-

fication is so obvious that I have not deemed it necessary to show it.

Having thus described my invention, I claim as new—

1. In a motor-engine, a perforated elastic diaphragm actuated by an elastic fluid, imparting motion to a detached piston.

2. In a motor-engine, a perforated elastic diaphragm, actuated by an elastic fluid, and a detached piston, which, during a part only of the stroke, prevents the escape of elastic fluid through the perforation by contact with said 75 diaphragm.

3. In a motor-engine, a perforated elastic diaphragm, actuated by an elastic fluid, which imparts motion to a detached piston through a part only of the stroke and resumes its normal position by its own elasticity, the exhaust meanwhile taking place through the perforation when by momentum it is uncovered by the travel of the piston.

4. A motor-engine provided with an elastic 85 perforated diaphragm, actuated by an elastic fluid, which imparts motion to the piston and is retracted by its own elasticity, the exhaust taking place through the perforation, substantially as described.

5. A motor-engine provided with an elastic 90 perforated diaphragm, actuated by an elastic fluid, which imparts motion to the piston, and, during a part of the stroke, prevents the escape of the elastic fluid through the perforation in 95 said diaphragm, in the manner described.

6. The elastic perforated diaphragm A, in combination with the piston-head B, operating substantially as described, and for the purpose specified.

7. The elastic perforated diaphragm A, in combination with the piston-head B and mechanism for converting reciprocating into rotary motion, substantially as described.

8. A motor-engine in which an elastic 105 diaphragm, actuated by an elastic fluid, imparts motion to the piston, and in which the said diaphragm and piston are in contact only during a portion of the stroke.

9. The construction, substantially as herein set forth, consisting, essentially, of a chamber or cylinder receiving a continuous supply of elastic fluid under pressure, an elastic perforated diaphragm, a detached piston so arranged as to prevent the escape of elastic 115 fluid through the perforation when in contact with said diaphragm, and devices for converting reciprocating into rotary motion, all operating substantially as described.

In testimony whereof I affix my signature in 120 presence of two witnesses.

WILLIAM E. EASTMAN.
